UNITED STATES PATENT OFFICE.

EDWARD J. BALLGOE, OF MIDWEST, WYOMING.

OIL BURNER.

Application filed February 14, 1923. Serial No. 254,270.

The present invention relates to improvements in oil burners and has for its principal object to provide a simple and efficient device for regulating the amount of fuel that is discharged from the spray nozzle for commingling with the air under pressure as the same is discharged from its nozzle, whereby the fuel will be properly atomized at its point of ignition.

- 5 10 One of the important objects of the present invention is to provide an oil burner that includes a longitudinally movable air pipe that is arranged within a fuel pipe, the outer end of the air pipe forming a needle valve for cooperation with the discharge opening 15 of the spray nozzle associated with the outer end of the fuel pipe, means being arranged within the spray nozzle of the fuel pipe for effecting a whirling action of the fuel.
- 20 25 A still further object of the invention is to provide an oil burner of the above mentioned character that is simple in construction, inexpensive, strong and durable, and further well adapted to the purpose for which it is designed.

Other objects and advantages of the invention will become apparent from the following description when taken in connection with the accompanying drawing.

- 30 In the accompanying drawing wherein like reference characters indicate corresponding parts throughout the same:

Figure 1 is a longitudinal sectional view through the oil pipe and the spray nozzle arranged on the outer end thereof, the air pipe being shown in elevation and

Figure 2 is a vertical sectional view taken substantially upon the line 2—2 of Figure 1.

In the drawing wherein for the purpose of illustration is shown the preferred embodiment of my invention, the numeral 1 designates a tubular head that is internally threaded at its respective ends. A pair of diametrically opposed nipples 2 and 3 extend laterally from the intermediate portion of the tubular head 1. An oil or gas supply pipe is adapted for connection with the inlet nipple 2 while a plug 4 is threaded in the other nipple in the manner as clearly shown in Figure 1.

A closure is provided for the outer end of the tubular head 1 and the same comprises a relatively short pipe section 5 that is threaded externally at its respective ends, the inner end thereof being threaded in the outer internally threaded end of the head 1. A cap

6 is threaded on the outer end of the pipe section 5 and a suitable packing washer 7 is interposed between the outer end of the pipe section 5 and the cap 6 in the manner as also clearly shown in Figure 1.

A fuel pipe 8 has its rear end threaded into the forward end of the tubular head 1 and carried by the forward end of this fuel pipe is the spray nozzle unit designated generally by the numeral 9. This spray nozzle unit includes the complementary circular casing sections 10 and 11, respectively, the same being open at their inner opposed sides and as is clearly shown in Figure 1, the casing section 11 is wider than the casing section 10, and furthermore the outer casing section 11 is threaded on the inner casing section 10, the rear side of the casing section 10 is formed with an enlarged circular opening and extending from the rear side of the inner section 10 around the opening is the internally threaded collar 12 that has threaded engagement with the forward end of the fuel pipe 8.

The outer or front side of the casing section 11 is formed centrally with a fuel discharge opening 13 and the outer edge portion of this opening or orifice is beveled as illustrated at 14 also in Figure 1.

Adapted for vertical disposition within the spray nozzle unit 9 is the circular disc 15, the same being formed at its front face with the forwardly extending lugs 16 that space the disc with respect to the front side of the outer casing section 11, the rear face 90 of the disc being adapted to abut against the forward edge of the inner circular casing section 10 in the manner as clearly illustrated in Figure 1.

The circular disc 15 is formed with an annular series of fuel emitting openings or apertures 17 and the same are arranged at an angle of approximately 45° whereby to effect a whirling action of the fuel as the same is discharged through the openings in the disc 100 into the forward end portion of the spray nozzle 9. The disc is further formed with an enlarged central threaded opening 18, the purpose of which will be presently apparent.

Also forming a salient part of the present invention is the air pipe 19 that is of a smaller diameter than the fuel pipe 9 and is arranged longitudinally through the fuel pipe as well as through the spray nozzle unit 9 and the head 1 at the respective ends of the fuel pipe. The rear end of this air pipe 19 extends through the cap 6 and is adapted to

receive air under pressure from any suitable source. A hand wheel 20 is arranged on the rear end portion of the air pipe 19 for the purpose of actuating the same to adjust the 5 air pipe.

The forward end of the air pipe 19 terminates in the tapered discharge nozzle 21 that extends through the fuel discharge opening 13 and the portion of the air pipe 19 directly inwardly of the discharge nozzle 21 is 10 externally threaded as indicated at 22 for cooperation with the threaded opening 18 formed in the central portion of the disc 15. The disc 15 provides a means for supporting 15 the forward end portion of the air pipe 19 and furthermore the threads 22 of the air pipe cooperate with the threads in the opening 18 for securing the air pipe in any longitudinally adjusted position so that the 20 tapered discharge nozzle 21 may be regulated with respect to the fuel discharge opening 13 for obvious purposes.

The air pipe 19 is adjusted longitudinally by turning the hand wheel 20. From the 25 foregoing description, it will be readily observed that air under pressure will be mixed with oil as the same is discharged through the opening 13 thus enabling the oil to be thoroughly atomized at its point of ignition. Furthermore, the disposition of the fuel 30 discharge openings 17 in the disc 15 will result in the fuel being subjected to a whirling action before being discharged through the opening 13 and will also tend to cool the 35 spray nozzle unit 9.

A burner of the above mentioned character can be used for various purposes and the same will at all times be positive and efficient in its operation.

While I have shown the preferred embodiment of my invention, it is to be understood that various changes in the size, shape and arrangement of parts may be resorted to without departing from the spirit of the invention and the scope of the appended claim. 40

Having thus described the invention, what I claim is:—

An oil burner of the class described comprising a fuel pipe having an inlet at its rear end, a spray nozzle unit arranged on the forward end of the pipe, said unit including complementary circular casing sections open at their inner opposed sides, the outermost section being threaded on the forward open end of the inner section, the outer side of the outer section being provided with a fuel discharge opening, an air pipe extending longitudinally toward the fuel pipe and having its forward end formed with an air discharge nipple for disposition through the fuel discharge opening, the rear end of the air pipe forming an inlet, a circular disc arranged vertically in the outer section of the spray nozzle unit for disposition against the forward edge of the inner section, lugs projecting forwardly from the outer face of the disc for engagement with the inner face of the outer side of the outer section to space the disc with respect to the fuel discharge opening, said disc being formed with a central threaded opening, the adjacent portion of the air pipe being threaded therethrough, a hand wheel on the rear end of the air pipe for adjusting the same longitudinally with respect to the fuel pipe, said disc being provided with a series of fuel emitting apertures. 55 60 65 70 75

In testimony whereof I affix my signature.

EDWARD J. BALLGOE.
